UNITED STATES PATENT OFFICE

OTTO VOGL, OF CHICAGO, ILLINOIS, ASSIGNOR TO CHICAGO PRINTED STRING CO., OF CHICAGO, ILLINOIS, A CORPORATION OF ILLINOIS

DESIGN FOR A SPOOL HOLDER OR SIMILAR ARTICLE

Application filed March 4, 1932. Serial No. 43,070. Term of patent 7 years.

To all whom it may concern:

Be it known that I, OTTO VOGL, a citizen of the United States, and a resident of the city of Chicago, in the county of Cook and State of Illinois, have invented a new, original, and ornamental Design for a Spool Holder or similar article, of which the following is a specification, reference being had to the accompanying drawings, forming a part hereof.

In the drawings:

I claim:

The ornamental design for a spool holder, or similar article, as shown.

OTTO VOGL.
